M. POPKIN.

CARBURETOR LOCK FOR INTERNAL COMBUSTION ENGINES.
APPLICATION FILED SEPT. 27, 1920.

Patented Mar. 14, 1922.

Inventor:
Morris Popkin,

Attys.

UNITED STATES PATENT OFFICE.

MORRIS POPKIN, OF MALDEN, MASSACHUSETTS.

CARBURETOR LOCK FOR INTERNAL-COMBUSTION ENGINES.

1,409,236.

Specification of Letters Patent. Patented Mar. 14, 1922.

Application filed September 27, 1920. Serial No. 412,997.

To all whom it may concern:

Be it known that I, MORRIS POPKIN, a citizen of the United States, and a resident of Malden, in the county of Middlesex and 5 State of Massachusetts, have invented an Improvement in Carburetor Locks for Internal-Combustion Engines, of which the following description, in connection with the accompanying drawings, is a specification, 10 like characters on the drawings representing like parts.

This invention relates to carburetor locks for internal combustion engines. An important object of the invention is to provide a carburetor lock of simple construction and yet one that cannot be tampered with without great difficulty and only with such expenditure of time as to render such tampering substantially out of the question.

20 In order that the principle of the invention may be readily understood, I have disclosed certain embodiments thereof in the accompanying drawing, wherein—

Fig. 1 is a view partially in side elevation and partially in vertical section of the preferred embodiment of my invention;

Fig. 2 is a plan view of a portion of the construction shown in Fig. 1;

Fig. 2^a is a view similar to Fig. 2 of a 30 slightly different form of my invention.

Fig. 3 is a vertical transverse section of a slightly modified form of my invention;

Fig. 4 is a vertical section of the construction shown in Fig. 3 upon the line 4—4 35 in said figure and looking toward the right in said figure; and

Fig. 5 is a transverse section upon the line 5—5 of Fig. 4.

It has heretofore been proposed to provide a valve to cut off the flow of liquid fuel to the carburetor of an internal combustion engine and to provide a lock for such valve. In all constructions with which I am familiar, however, the devices have been of complicated and expensive construction, and moreover have been of such a nature that they can more or less readily be tampered with, as, for example, by cutting out some part or otherwise providing a by-pass or 45 passage for the flow of fluid fuel to the carburetor around the locked valve, thus permitting a thief to escape with the car.

In accordance with my invention, an exceedingly simple construction is provided 50 and yet one that cannot readily be tampered with, thus rendering it exceedingly difficult

for a would-be thief to get away with the automobile, truck or other vehicle having an internal combustion engine.

Referring more particularly to the drawings, the body of a carburetor is indicated conventionally at 1 in Fig. 1, it being of any suitable construction and containing the usual parts or members not herein necessary to show or to refer to. The body 1 is desirably of metal and in the preferred embodiment of my invention has integrally cast or otherwise integrally formed therewith a projection 2, here shown as a lateral projection, which in turn has preferably integrally formed therewith a casing 3 adapted to receive a valve 4 and a lock 5. The integral structure thus far described is provided with a passage 6 for the gasoline or other fluid fuel, and tapped or otherwise 70 suitably attached to said passage is a threaded pipe 7 by which the gasoline or the like is supplied from the usual source.

The interior construction of the casing 3 may be varied in accordance with the scope 80 of my invention, but desirably there is provided a transverse web or part 8 having therein a longitudinal opening 9 for the reception of the valve 4, here shown as of a rotary type and having an opening 10 for 85 the passage of the gasoline or the like. Desirably above the web or the part 8 there is a recess or cavity 11, within which is stationarily mounted the lock 5 which may be of any suitable construction and which 90 therefore need not be shown in detail. Desirably the lock is of the so-called Yale type, there being provided the usual or necessary tumblers or other parts. The said lock 5 may have cast therewith or attached thereto 95 a cap or part 12 adapted to receive the end 13 of the lock, said end being provided with the usual slot or opening for the reception of the key 14.

Extending from the inner or lower end 100 of the lock 5 is the projection or member 15 that is turned by the key 14 with the rotatable or oscillatory part of the lock. The projection or member is adapted to cooperate in any suitable way with the valve 9. 105 As herein represented, the said valve is provided with a transverse slot 16 in its upper end to receive the said projection or member 15, so that when the latter is turned, the valve 4 may be turned into either an 110 open or closed position.

In order to secure the body of the lock

5 in the casing 3, I may provide any suitable construction. Herein for the purpose I have represented the body 5 as having two lateral ears 17, 18 receiving the threaded 5 ends 19, 20 of two bolts 21, 22 positioned in the transverse web 8, the heads of the bolts being accessible at the recess 23 provided at the end of the casing 3 opposite the lock 14. The said recess 23 may be closed in any 10 suitable manner as by a threaded cap 24.

Obviously it would be a matter of exceeding difficulty for a would-be thief to tamper with the device of the construction herein shown, as by cutting out the part carrying 15 the valve 4.

In the preferred embodiment of my invention, the casing 3 is integrally cast or otherwise formed with the body 1 of the carburetor. My invention, however, is not 20 limited to such integral construction, as within the scope of the invention the casing 3 may be secured to the carburetor in a preferably permanent manner, but in such a way as to permit my invention to be applied to 25 carburetors already in use, or of a usual construction or formation or it may be otherwise located within the scope of my invention. The best results are obtained by a carburetor having the parts of my invention 30 integrally formed therewith. It is evident that the lateral projection 2 need not be of the form indicated in Figs. 1 and 2, but may merge into both the carburetor body 1 and casing 3 in such a way as absolutely to prevent any separation of the casing 3 from the 35 carburetor body 1 by sawing or otherwise, as shown in Fig. 2^a.

The key 14 provided for each carburetor lock is preferably of a distinctive form and 40 not interchangeable with other keys. This would minimize the chances that a would-be thief carries with him a key by which he can operate the valve 4.

Having thus described one illustrative embodiment of my invention, I desire it to be understood that although specific terms are employed, they are used in a generic and descriptive sense and not for purposes of limitation, the scope of the invention being set 45 forth in the following claims:

1. In a fuel lock mechanism for carburetors, the combination with a carburetor of a casing, a lock wholly positioned within said casing and capable of retaining a valve in 50 closed position, said lock being adapted to receive a key through a wall of said casing, the latter having a relatively heavy, internal, transverse web, means within said casing engaging said lock and said web to secure said 55 lock in place in said casing, said web having a valve seat and a valve adapted to said seat and adapted to be secured by said lock, and a fuel line connection leading to said carburetor and in which line said casing is positioned.

2. In a fuel lock mechanism for carburetors, and the like, of vehicles, a casing having communication with the liquid fuel line of the vehicle, a lock wholly positioned within said casing and capable of retaining a valve 70 in closed position, said lock being adapted to receive a key through a wall of said casing, the latter having a relatively heavy, internal, transverse web, and means within said casing engaging said lock and said web 75 to secure said lock in place in said casing, said web having a valve seat and a valve adapted to said seat and adapted to be secured by said lock.

3. In a fuel lock mechanism for carburetors, the combination with a carburetor of an integral casing, a lock wholly positioned within said integral casing and capable of retaining a valve in closed position, said lock being adapted to receive a key through a 80 wall of said casing, the latter having a relatively heavy internal transverse web, and means within said casing engaging said lock and said web to secure said lock in place in said casing, said web having a valve seat and 85 a valve adapted to said seat and adapted to be secured by said lock.

4. In a fuel lock mechanism for carburetors, the combination with a carburetor of an integral casing, a lock wholly positioned 90 within said integral casing and capable of retaining a valve in closed position, said lock being adapted to receive a key through a wall of said casing, the latter having a relatively heavy, internal, transverse web integral with the casing and one or more lock members carried by said web and engaging said lock to hold the latter in place in said casing, said valve having a valve seat, and a valve adapted to said seat and adapted to be 95 secured by said lock.

5. In a fuel lock mechanism for carburetors, the combination with a carburetor of an integral casing, a lock wholly positioned 100 within said integral casing and capable of retaining a valve in closed position, said lock being adapted to receive a key through a wall of said casing, the latter having a relatively heavy, thick, internal, transverse web integral with the casing, said web having a 105 valve seat and fuel passages leading to and from the valve in said seat, and means within the casing and engaging said lock and said web to secure said lock in place in said casing.

6. In a fuel lock mechanism for carburetors, the combination with a carburetor of an integral casing, a lock wholly positioned 110 within said integral casing and capable of retaining a valve in closed position, said lock being adapted to receive a key through a wall of said casing, the latter having a relatively heavy and thick transverse web, a valve seat in said web and relatively remote 115 from the wall of said casing, a valve adapted 120 to

to said seat and adapted to be operated by said lock, and fuel passages in said web to communicate with the valve, and means engaging said lock and said web to secure the 5 lock in place in said casing.

7. In a fuel lock mechanism for carburetors, the combination with a carburetor of an integral casing, a lock wholly positioned within said integral casing and capable of 10 retaining a valve in closed position, said lock being adapted to receive a key through a wall of said casing, the latter having a rela-

tively heavy and thick transverse web, a valve seat in said web and relatively remote from the wall of said casing, a valve adapted 15 to said seat and adapted to be operated by said lock, fuel passages in said web to communicate with the valve and a plurality of bolts passing lengthwise of the casing through said web and threaded into said lock 20 to secure the latter in place.

In testimony whereof, I have signed my name to this specification.

MORRIS POPKIN.
